[57] CLAIM

The design for support for strainer cones, as shown and described.

DESCRIPTION

FIG. 1 is a perspective view of a support for strainer cones showing my new design;

FIG. 2 is a side view thereof;

FIG. 3 is a top view thereof;

FIG. 4 is a further side view of FIG. 2, rotated approximately 30 degrees;

FIG. 5 is the opposite side view of FIG. 4;

FIG. 6 is a bottom view thereof.

FIG. 1

FIG. 3

FIG. 2

FIG. 4

FIG. 5

FIG. 6
